CONVERSION OF HYDROCARBONS

Kenneth D. Uitti, Chicago, Ill., assignor to Universal Oil Products Company, Chicago, Ill., a corporation of Delaware

Application September 9, 1940, Serial No. 355,957

2 Claims. (Cl. 260—683.1)

This is a continuation-in-part of my co-pending application Serial No. 297,392, filed September 30, 1939.

The invention is directed to an improved method of producing liquid fractions of high antiknock value boiling within the range of gasoline from normally gaseous hydrocarbons, such as butanes or butanes and propane. The process involves a combination of concomitantly operated interdependent conversion steps which cooperate to produce the desired final results.

In addition to appropriate separating steps of well known form for separating the products of the several conversion steps into selected fractions, the process involves a dehydrogenating system wherein butanes or butanes and propane are converted into substantial yields of corresponding olefins, followed by separate catalytic polymerization of the butylenes and propylene thus produced to convert the same into high yields of liquid polymers boiling within the range of gasoline and of good antiknock value. The butylene polymerizing step being followed by catalytic hydrogenation of the polymer gasoline produced therein to form a hydrogenated polymer product of improved antiknock value. Residual butanes which remain unconverted after subjecting the butane-butylene fractions from the dehydrogenating operation to catalytic polymerization treatment are returned to the dehydrogenating operation for further conversion into readily polymerizable olefins. Residual propane, which remains unconverted after subjecting the propane-propylene fraction from the dehydrogenating operation to catalytic polymerization, may also be returned to the dehydrogenating operation to convert substantial quantities thereof into propylene.

The dehydrogenating operation may be either catalytic or thermal and when both propane and butanes are to be dehydrogenated, they may be subjected to dehydrogenation in commingled state or separately. The preferred method of operation, when separate hydrogenating steps are employed, is to separate the materials to be dehydrogenated into a fraction consisting predominantly of normal butanes and a fraction consisting predominantly of isobutane and propane, catalytically dehydrogenating the normal butane fraction and thermally dehydrogenating the fraction consisting predominantly of iso-butane and propane. This preferred method of operation is advantageous in that it permits relatively cheap thermal treatment of the iso-butane and propane which will give good yields of iso-butylenes and

propylene, whereas such thermal treatment of the normal butanes would result in the excessive production of light gases and only minor yields of butylenes. Separate catalytic dehydrogenation of the normal butanes, on the other hand, may be controlled to give good yields of butylenes.

The polymerizing operation, to which butanes and butylenes recovered from the products of the dehydrogenating operation are supplied, is conducted in the presence of a polymerizing catalyst under conditions regulated to convert substantially all of both the iso and normal butylenes into high yields of liquid polymers boiling within the range of gasoline, leaving butanes as the essential components of the normally gaseous fractions in the resulting products and thereby serving as a means of isolating substantially pure butanes for further dehydrogenating treatment in addition to its function of producing good antiknock polymer gasoline.

The polymer gasoline produced in the butylene polymerizing operation will contain substantial quantities of iso-octenes formed by polymerization of the iso-butylenes and may advantageously be hydrogenated to form a saturated polymer gasoline of improved antiknock value and low bromine number or acid heat test, suitable for aviation gasoline. This product contains substantial quantities of iso-octanes formed by hydrogenation of the iso-octenes. The hydrogenating operation is catalytically conducted and preferably employs light hydrogen-containing gases formed in the dehydrogenating operation as a source of hydrogen.

The polymerizing operation, to which propane and propylene separately recovered from the products of the dehydrogenating operation are supplied, also employs a polymerizing catalyst and is operated to convert substantially all of the propylene into high yields of liquid polymers boiling within the range of gasoline and of good antiknock value. Hydrogenation of this product is not contemplated since such treatment will not improve its antiknock value. Due to its olefinic nature, it does not meet the acid-heat test requirements for aviation gasoline, but is highly desirable for blending with straight-run or cracked gasoline of inferior antiknock value to form a good antiknock motor gasoline. The propylene polymerizing step, in addition to its function of producing good antiknock polymer gasoline, serves to isolate substantially pure propane from propylene, since the propane remains substantially unconverted while the propylene is polymerized. The propane thus obtained may,

when desired, be recycled to the dehydrogenating operation for the production therefrom of additional quantities of propylene.

One aspect of the invention resides in the novel and advantageous combination of cooperative and interdependent steps which constitute the process as a whole. However, the invention is not limited to a combination of all the steps provided, since various lesser combinations contemplated by the invention and herein disclosed, will be found advantageous and are believed to involve patentable novelty. Each of the individual steps of the process and the cooperative combination thereof, which constitutes the integrated process disclosed, will be discussed in greater detail in conjunction with the description of the accompanying drawing.

Figure 1 of the drawing is essentially a flow diagram illustrating the cooperative relationship between the various major steps of the process and Figure 2 is a diagrammatic illustration of the dehydrogenating operation as employed for thermally dehydrogenating a mixture of isobutane and propane with separate catalytic dehydrogenation of normal butanes.

Referring now to Figure 1 of the drawing, the normally gaseous hydrocarbons to be dehydrogenated, which may consist predominantly of butanes or may comprise both butanes and propane, are supplied from any desired source through line 1 to the dehydrogenating system 2 wherein they are subjected to either catalytic or thermal dehydrogenation treatment under conditions regulated to produce therefrom substantial yields of readily polymerizable olefins, such as butylenes or butylenes and propylene.

The products of the dehydrogenating operation are directed from the dehydrogenating system 2 through line 3 to separation into the desired selected fractions in zone 4 which comprises fractionating, condensing and collecting equipment of any suitable well known form. When the dehydrogenating operation involves the thermal conversion of either butanes or propane or a mixture thereof, side reactions, such as cracking and polymerization, which accompany the thermal dehydrogenation treatment will result in the production of some normally liquid fractions which are removed from separating zone 4 through line 5 to storage or elsewhere, as desired. A normally gaseous fraction, consisting predominantly of butanes and butylenes, is separately recovered from the products of the dehydrogenating operation and directed from zone 4 through line 6 to the butylene polymerizing system 7, which will be later described. Another normally gaseous fraction, consisting essentially of propane and propylene, is separately recovered from the products of the dehydrogenating operation and directed from zone 4 through line 8 to the propylene polymerizing system 9, which will be later described. A fraction consisting essentially of gases having 2 and less carbon atoms in the molecule and containing hydrogen gas formed in the dehydrogenating operation are separately removed from zone 4 through line 10 and may be removed, all or in part, from the system through line 11 to storage or elsewhere, as desired, or preferably, regulated quantities of the hydrogen-containing gases are utilized as a source of hydrogen in the catalytic hydrogenating operation succeeding the butylene polymerizing step. When so utilized, hydrogen-containing gases are directed from line 10 through line

12 to the catalytic hydrogenating system 13, which will be later described.

The dehydrogenation of paraffinic hydrocarbon gases having 3 and 4-carbon atoms in the molecule is only one method of producing butylenes and propylene for polymerization. Hydrocarbon oil cracking operations, either thermal or catalytic, comprise another well known source of such materials and the invention specifically contemplates the polymerization of propylene and/or butylenes from any external source, together with the corresponding olefins formed in the dehydrogenating operation. This may be accomplished, for example, by supplying a mixture of normally gaseous fractions containing substantial quantities of the desired olefins, such as, for example, olefin-containing gases produced in the cracking of hydrocarbon oils, to the same separating system whereto the products of the dehydrogenating operation are supplied. In the case here illustrated, such extraneous gases may be introduced into the system by supplying the same through line 13 to separating zone 4 or extraneous normally gaseous fractions, consisting predominantly of butanes and butylenes, may be supplied to the butylene polymerizing system through line 14 and, when desired, extraneous normally gaseous fractions, consisting predominantly of propane and propylene, may be supplied to the propylene polymerizing system through line 15.

The butylene polymerizing system 7 is operated to convert substantially all of the butylene components of the 4-carbon atom gases supplied thereto and such polymerization is accomplished in the presence of a catalyst capable of promoting this reaction. The catalyst which I preferably employ is the well known "solid phosphoric acid" catalyst which consists essentially of granules or preformed pellets of a relatively inert porous carrier, such as diatomaceous earth or kieselguhr impregnated with a mixture of ortho and pyro phosphoric acids and calcined prior to their use. Catalysts of this type are preferably employed in the form of one or a plurality of stationary beds through which the reactants are passed after being heated to the temperature required for conducting the reaction. Since the polymerizing reaction is strongly exothermic, provision is preferably made for preventing an excessive temperature rise in the catalyst bed or beds by disposing the same in reactors of the heat exchanger type and circulating a cooling medium therethrough in indirect heat exchange relation with the catalyst and the reactants and conversion products. Provision may also be made, when desired, for periodically reactivating the catalyst in situ by burning therefrom deleterious heavy conversion products deposited thereon during the conversion reaction in a stream of oxygen-containing gases. It is also important to obtain an optimum degree of hydration of the catalyst during processing and particularly during reactivation. These features are all taught in the prior art and illustration of the various means whereby they may be accomplished is, therefore, unnecessary in the present instance.

It is also possible to accomplish substantially complete conversion of the butylenes in the butylene polymerizing step with other well known polymerizing catalysts, such as, for example, sulfuric acid either in liquid state or on a relatively inert granular carrier of a porous nature, such as diatomaceous earth or kieselguhr. Liquid

phosphoric acid may also be employed as may aluminum chloride, preferably in conjunction with hydrogen chloride, and boron fluoride, preferably in conjunction with hydrogen. Any of these or other known polymerizing catalysts capable of accomplishing the desired results may be employed within the scope of the invention.

Operating conditions under which substantially complete polymerization of the butylenes may be accomplished are also familiar to those skilled in the art. They will vary considerably depending upon the catalyst employed and the ratio of iso-butylenes to normal butylenes in the charge. When employing solid phosphoric acid catalyst at temperatures of from about 300 to about 550° F. will be found suitable, preferably with a superatmospheric pressure which may range from 200 to 1500 pounds, or thereabouts, per square inch. In general, more severe conditions should be employed with increased ratios of normal to iso-butylenes and/or with decreased contact time in the reaction zone.

The products of the butylene polymerizing operation are directed from zone 7 through line 16 to the succeeding separating system 17 which will ordinarily comprise a plurality of well known fractionating steps and wherein the products are separated into the desired selected fractions. Polymer gasoline of the desired end-boiling point and which is preferably stabilized to the desired vapor pressure is directed from separating zone 17 through line 18 to the catalytic hydrogenating step 19, which will be later described. Heavier normally liquid products formed in the polymerizing operation are directed from zone 17 through line 20 to storage or elsewhere, as desired. The residual normally gaseous products of the polymerizing operation, which will consist predominantly of butanes, are separately removed from zone 17 and recycled through line 21 to the dehydrogenating operation for further conversion therein to produce additional yields of readily polymerizable olefins.

Hydrogenation of the polymer gasoline produced in the butylene polymerizing step is accomplished in hydrogenating system 19 in the presence of a catalyst which promotes the hydrogenating reaction. One of the catalysts which has been found most suitable for this purpose consists essentially of nickel on porous particles of a relatively inert siliceous carrier, such as diatomaceous earth or kieselguhr. This catalyst may be produced, for example, by precipitating nickel carbonate on the carrier, pressing or extruding the mixture into pills or pellets which are dried and reduced in an atmospheric of hydrogen at a temperature of the order of 750° F. However, the specific nature of the hydrogenating catalyst and the method of its manufacture are not a novel part of the present invention and any other well known hydrogenating catalyst may be employed within its scope. Some of the other materials which are suitable comprise, for example, oxides of chromium, molybdenum and tungsten either alone or in combination and with a nickel catalyst of the nature above mentioned. The desired hydrogenating reaction may be accomplished at a temperature of from 250 to 450° F. or thereabouts, and at a superatmospheric pressure of from 150 to 250 pounds or more per square inch.

The products of the hydrogenating operation are supplied from zone 19 through line 22 to separating zone 23 which may comprise suitable fractionating equipment of any well known form

and wherein the hydrogenated polymer product is separated from the unused hydrogen or hydrogen-containing gases. The hydrogenated polymer gasoline, which will include substantial quantities of iso-octanes and is a substantially saturated product of low bromine number and of materially improved antiknock value, as compared with the polymer gasoline from which it is formed, is withdrawn from zone 23 through line 24 to storage or elsewhere, as desired. Hydrogen or hydrogen-containing gases are removed from zone 23 through line 25 and may be discharged, all or in part, from the system. Preferably, however, since a quantity of hydrogen considerably in excess of that theoretically required to accomplish substantially complete hydrogenation of the unsaturated polymer gasoline is required for best results, hydrogen or hydrogen-containing gases from zone 23 are preferably recycled to the hydrogenating zone through lines 26 and 12 in quantities regulated to maintain the desired excess of hydrogen from this zone. When hydrogen or hydrogen-containing gases formed in the dehydrogenating operation are not employed as the sole source of hydrogen in zone 19, hydrogen or gases rich in hydrogen may be supplied to zone 19 from an external source through line 27.

The propylene polymerizing operation is conducted in zone 9 in the presence of a polymerizing catalyst under conditions regulated to convert all or substantial quantities of the propylene into high yields of liquid polymers, a large portion of which boil within the range of gasoline and are of high antiknock value. Solid phosphoric acid catalyst of the nature above mentioned is preferably employed in this step, although any other well known polymerizing catalyst capable of accomplishing the desired results may be employed within the scope of the invention. With the solid phosphoric acid catalyst, the propylene polymerizing system may be of the same general type referred to in conjunction with the preceding description of the butylene polymerizing system. Temperatures of the order of 350 to 550° F., or thereabouts, and a superatmospheric pressure within the approximate range of 200 to 1500 pounds per square inch may be employed in the propylene polymerizing system when the solid phosphoric acid catalyst is utilized.

The products resulting from the propylene polymerizing operation are directed from zone 9 through line 28 to the succeeding separating system 29 which will ordinarily comprise a plurality of fractionating steps of any suitable well known form. Polymer gasoline of the desired end-boiling point is removed from zone 29 through line 30 to storage or elsewhere, as desired. Heavier liquid products formed in the polymerizing operation are separately removed from zone 29 through line 31 to storage or elsewhere, as desired. The residual normally gaseous products of the propylene polymerizing step, which will consist predominantly of propane, are separately withdrawn from zone 29 through line 32 and may be removed from the system or, when desired, may be recycled, all or in part, through line 33 to the dehydrogenating system for further conversion therein to produce additional yields of propylene.

Referring now to Figure 2, which, as previously mentioned, diagrammatically illustrates a more specific embodiment of the dehydrogenating stage of the system illustrated in Figure 1, a separating zone 34 is provided preceding the dehydrogenating zone, to which separating zone the residual butanes (both iso and normal) from separating

zone 17 of Figure 1 are supplied through line 21. The charging stock, which may be butanes or a mixture of butanes and propane is also supplied to separating zone 34 through line 1.

Separating zone 34 may comprise any suitable well known form of fractionating equipment and its function is to separate from the normally gaseous materials supplied thereto, a fraction consisting predominantly of normal butanes and a fraction consisting predominantly of iso-butane or iso-butane and propane. Fortunately, iso-butane is the lowest boiling of the 4-carbon atom gases, having a boiling point of approximately 11° F., while the lightest of the normal butanes boils at approximately 31° F. The iso-butane or propane and iso-butane will therefore readily separate as the overhead stream from the normal butanes, as bottoms, upon fractionation. The normal butanes are directed from zone 34 through line 35 to the catalytic dehydrogenating zone 2A of the dehydrogenating system and the iso-butane or mixture of iso-butane and propane is directed from zone 34 through line 36 to the thermal dehydrogenating zone 2B of the dehydrogenating system together with propane, from the propylene polymerizing step of Fig. 1, supplied through line 33. Products resulting from the catalytic dehydrogenation treatment of the normal butanes are removed from zone 2A through line 3A, while the products resulting from the thermal dehydrogenation treatment of the iso-butane and propane are removed from zone 2B through line 3B and, in the case here illustrated, both streams of products are directed through line 3 to the separating system 4 of Figure 1.

The operating conditions required for dehydrogenating various paraffinic hydrocarbons are now well known to those skilled in the art. Pressures and temperatures, and particularly the latter may be varied considerably with different contact times and somewhat different conditions are optimum with different catalysts, which latter are now well known. It is therefore considered unnecessary to discuss in detail all of the many possible variations and the following will serve to illustrate suitable conditions under which the preferred embodiment of the process provided by the invention may be conducted using a catalyst for dehydrogenating the normal butanes which consists essentially of preformed relatively porous pellets or granules of alumina or other refractory material and one or more of the oxides of chromium, molybdenum, vanadium and cerium, and employing thermal dehydrogenating conditions for the mixture of iso-butane and propane.

The catalytic dehydrogenation operation may employ a temperature of from 1000 to 1200° F., or thereabouts, with a pressure which does not exceed 100 pounds per square inch, or thereabouts, lower pressures down to substantially atmospheric being preferred. The space velocity, expressed as cubic feet of reactants subjected to treatment per hour, per cubic feet of space occupied by the catalyst bed is preferably within the range of 1000 to 2000 for converting normal butanes and 500 to 1500 for converting a mixture of butanes and propane.

The thermal dehydrogenating operation is also preferably conducted at substantially atmospheric or relatively low superatmospheric pressure although higher pressures up to 750 pounds or more per square inch may be employed when desired. The temperature employed may range

from 1050 to 1200° F., or thereabouts and the conversion time is preferably within the range of 50 to 150 seconds for mixtures of iso-butane and propane. A shorter time factor which may range, for example, from 20 to 60 seconds is preferred when substantial quantities of normal butanes are present.

Either thermal or catalytic dehydrogenation of a mixture of iso and normal butanes, alone or 10 with propane, may be accomplished within the range of conditions above given, but thermal treatment of the normal butanes, either alone or in admixture, under these conditions will result in extensive cracking thereof with consequent low yields of butylenes and high yields of lighter gases. Thermal treatment is of course, less expensive and may be employed for converting the iso-butane and propane with less cracking than in the case of normal butanes. Low 15 pressure operation is preferred in any case to high pressure and is essential in catalytic dehydrogenation. High pressure operation is less expensive in thermal dehydrogenation but favors cracking and therefore is preferred only when 20 high yields of butylenes, which will polymerize to a higher octane number product as compared with that resulting from the polymerization of propylene, are not essential, i. e. when the process 25 is operated for the production of high yields of 30 motor gasoline rather than high yields of aviation gasoline.

As an example of one specific operation of the process, which is not to be construed as a limitation; the charging stock supplied to the dehydrogenating system is a mixture of iso and normal butane from an external source, to which residual butanes from the butylene polymerizing step and residual propane from the propylene polymerizing step are added. The butanes are separated 35 by fractionation into two components one of which consists predominantly of iso-butane and the other consisting predominantly of normal-butane. The iso-butane is commingled with a fraction consisting predominantly of propane 40 from the propylene polymerizing step and the mixture is subjected to thermal dehydrogenation at a temperature of approximately 1070° F. and at substantially atmospheric pressure, the time 45 during which it is exposed to these conditions being about 100 seconds. The normal butane fraction is subjected to catalytic dehydrogenation, in the presence of a catalyst of the preferred type 50 above mentioned, at a temperature of approximately 1100° F., and at substantially atmospheric pressure, with a space velocity of about 1500 cubic 55 feet per hour, per cubic feet of space occupied by the catalyst bed.

The products of both dehydrogenating steps are fractionated to separate therefrom a fraction 60 consisting predominantly of butylenes and butanes, a fraction consisting predominantly of propylene and propane, and a lighter fraction consisting predominantly of gases having two and less carbon atoms in the molecule and rich in 65 hydrogen.

The butane-butylenes fraction from the dehydrogenating system is subjected to catalytic polymerization in the presence of solid phosphoric acid catalyst at a temperature of approximately 70 375° F. and at a superatmospheric pressure of about 1000 pounds per square inch, with a space velocity of approximately 20 gallons of reactants per hour, per cubic feet of space occupied by the catalyst bed.

Normally gaseous fractions of the products re-

sulting from the butylene polymerizing operation consist predominantly of butanes and are recycled to the prefractionating zone of the dehydrogenating system.

Polymer gasoline formed in the butylene polymerizing step, contains a high percentage of isooctenes and is hydrogenated in the presence of a nickel catalyst, such as above mentioned, with hydrogen in the light gas stream from the dehydrogenating system. The hydrogenating zone is operated at a temperature of approximately 350° F. and at a superatmospheric pressure of about 200 pounds per square inch. Unused hydrogen is recycled and the hydrogenated polymer gasoline is recovered. This product amounts to approximately 23 gallons per thousand cubic feet of butanes charged to the system. It has an octane number of approximately 90 as determined by the motor method and, being substantially saturated, is well within the acid heat test requirements for aviation gasoline.

The propane-propylene fraction derived from the dehydrogenating system is subjected to separate catalytic polymerization, using solid phosphoric acid as the polymerizing catalyst, at a temperature of approximately 425° F., and a superatmospheric pressure of about 1200 pounds per square inch, the space velocity being approximately 18 gallons per hour per cubic feet of space occupied by the catalyst bed.

Normally gaseous fractions of the products from the propylene polymerizing step, which consist predominantly of propane, are recycled to the thermal dehydrogenating step. The polymer gasoline produced in the propylene polymerizing operation is recovered and amounts to approximately 2 gallons per thousand cubic feet of bu-

tane charging stock supplied to the system. It has an octane number of approximately 82, as determined by the motor method and is suitable for blending with gasoline of inferior antiknock value to improve the octane rating of the latter.

I claim as my invention:

1. A process for producing more valuable products from a hydrocarbon mixture containing butanes and propane which comprises separating 10 from said mixture a fraction consisting predominantly of normal butanes and a fraction consisting predominantly of isobutane and propane, catalytically dehydrogenating the first-named fraction and thermally dehydrogenating the second-mentioned fraction, commingling and separating from the resultant products a butane-butene fraction and a propane-propene fraction, subjecting the butane-butene fraction to polymerization, subjecting the propane-propene fraction to polymerization under independently controlled conditions, returning residual normal butane from the first-mentioned polymerizing step to the catalytic dehydrogenating step, and returning residual propane from the second-mentioned polymerizing step to the thermal dehydrogenating step.

2. The process as defined in claim 1 further characterized in that the residual butane is returned to the catalytic dehydrogenating step by being supplied to the first-mentioned separating step for treatment therein together with said hydrocarbon mixture while the residual propane is returned to the thermal dehydrogenating step by being commingled with said isobutane and propane from the first-mentioned step.

KENNETH D. UTTI.
